CLAIM

We claim the ornamental design for the multi port hub, as shown and described.

DESCRIPTION

FIG. 1 is an isometric view the multi port hub design; FIG. 2 is a right side view of the multi port hub design of FIG. 1; FIG. 3 is a left side view of the multi port hub design of FIG. 1; FIG. 4 is a front view of the multi port hub design of FIG. 1; FIG. 5 is a rear view of the multi port hub design of FIG. 1; FIG. 6 is a top view of the multi port hub design of FIG. 1; FIG. 7 is a bottom view of the multi port hub design of FIG. 1; FIG. 8 is a rear view of the multi port hub design of FIG. 5 with the cover removed; FIG. 9 is an isometric view of the multi port hub design of FIG. 1 with the cover removed; and, FIG. 10 is an isometric view of the multi port hub design of FIG. 1 with the cover and base removed.

The claimed design is directed to the appearance of the hub in its assembled state and is shown partially disassembled in FIGS. 9 and 10 for the purpose of clarifying aspects of the assembled design that may not be apparent from the other views.
